UNITED STATES PATENT OFFICE.

JASON S. BENTZ, OF COLUMBUS, OHIO.

DESIGN FOR A DISK FOR LAWN-POOL.

SPECIFICATION forming part of Design No. 27,399, dated July 20, 1897.

Application filed June 11, 1897. Serial No. 640,386. Term of patent 14 years.

To all whom it may concern:

Be it known that I, JASON S. BENTZ, a citizen of the United States, residing at Columbus, in the county of Franklin and State of Ohio, have invented and produced a new and original Design for Lawn-Pool Disks; and I do hereby declare the following to be a full, clear, and exact description of the same, reference being had to the accompanying drawings, forming a part thereof.

In the drawings referred to, Figure 1 is a top plan view of a disk embodying my design. Fig. 2 is a sectional view on the line $x-x$ of Fig. 1, and Fig. 3 is a plan view of the lower side of the disk.

Geometrically the disk is of the form of a frustum of a flattened cone, with a hole or pocket at the apex or top.

In the several views of the design, 1 designates the base, that is shown flat and circular. 2 designates the cone, which is smooth and of the form, and 3 designates the pocket or plate for the game of lawn-pool, smooth or regular conical or and the hole or pocket 3.

What I claim is—

The design for a disk or plate of lawn-pool, substantially as shown.

In testimony whereof I affix my signature in presence of two witnesses.

JASON S.
